FRIEDRICH L. HEYER, OF CHICAGO, ILLINOIS.

ATTACHMENT FOR AUTOMOBILES.

1,249,396.

Specification of Letters Patent. Patented Dec. 11, 1917.

Application filed October 4, 1916. Serial No. 123,634.

To all whom it may concern:

Be it known that FRIEDRICH L. HEYER, a citizen of the United States, residing at Chicago, in the county of Cook and State of Illinois, has invented certain new and useful Improvements in Attachments for Automobiles, of which the following is a specification.

The essential object of this invention is to provide an attachment for automobiles and similar vehicles whereby some of the circuits necessary to the starting and igniting systems or other operating parts are predeterminedly opened, thus obstructing operation of the vehicle, which circuit or circuits are adapted to be closed only upon proper manipulation of a key with which the owner of the vehicle, of course, will be provided.

In the drawings, and by way of example, two circuits are shown, one of which includes a battery and wires leading to and from the ignition system. The second circuit must be provided with a suitable source of current supply (not shown) and extends to and from the self-starter of the machine. In said drawings, Figure 1 is a front elevation of an apparatus embodying the invention; Fig. 2 is an interior view showing the movable parts in the positions in which both the starting and igniting circuits are broken; Fig. 3 is an interior view showing the movable parts in another position, the circuits being broken, but part of the ignition system being closed; Fig. 4 is an interior view showing the parts in the position assumed when both of the circuits are closed; Fig. 5 is a section on the line 5—5, Fig. 4; Fig. 6 is an interior view of the removable plate which forms part of the outer casing and which covers over or conceals the operating parts shown in Figs. 2, 3, and 4; Fig. 7 is a view similar to Fig. 5, the parts being shown in elevation rather than in section; Fig. 8 is a detail showing the mechanism for breaking the ignition circuit; and Fig. 9 is a perspective detailed view of one of the movable parts shown in Fig. 8.

The operating parts are all contained within a shell or casing 1, preferably made of metal, and provided with lugs 2 perforated at 3, by which the casing and the parts contained therewithin may be securely fastened to the front dashboard of the automobile. An annular disk 4 of insulation provides a suitable base to which most of the conducting and moving parts are secured, and, for

the purpose of additional safety, a second insulating member 5 may be provided intermediate the metallic casing 1 and the insulating base 4.

From the positive pole 6 of the battery or generator 7, the wire 8 runs to the binding-post 11 which is secured to the conducting plate 12. A spring-contact 13 depends from member 12, while a similar spring-contact 14 is connected to conducting plate 15 provided with the binding-post 16. Upon the opposite side of the device are similar spring-contacts 17 and 18 connected, respectively, with conducting-plates 19 and 20 provided with the binding-posts 21 and 22.

Screws 23 secure the stud or boss 24 upon the insulating base 4, and the stem 25 is adapted to move vertically through a suitable perforation 26 in said boss 24. At the bottom of the stem 25 and extending substantially at right angles thereto is a knife-switch formed of a strip of insulation 27, on each side of which are contact plates 28 and 29. The insulation 27 is wider than the contact surfaces 28 and 29, and when the parts are in the position shown in Fig. 2 of the drawings the spring contacts 13, 14, 17, and 18 will engage the insulating member 27 and the circuit will be broken, but when (by the means hereinafter described) the knife formed of the parts 27, 28, and 29, is elevated or moved to the position of Figs. 3 and 4, said spring-contacts 13 and 14 will engage the conducting member 29, the spring-contacts 17 and 18 will engage the conducting member 28, and, in that manner, the current will flow from the plate 12 successively through the members 13, 29, and 14 to the plate 15 and binding-post 16. At the same time the current will flow from the binding post 22 passing successively through members 22, 20, 18, 28, 17, and 19 to the binding-post 21.

The stem 25 is notched or slotted at 30, and the U-shaped locking catch 31, which is fitted over the stud or boss 24, is provided with the slot 32 through which the stem 25 is adapted to pass, as well as with the web 33 which seats in the notch 30 when the parts are in the position shown in Fig. 8. A helical spring 34 is interposed between the right hand end (Figs. 5 and 7) of the boss 24 and the cross-arm 35 of the sliding catch 31, said helical spring 34 being adapted to encircle a pin 36 which slides within the recess 37, said pin 36 being adapted to retain

said spring 34 in proper position. A button 38 projects outwardly through a perforation 39 formed in the removable cover 40. The stem 25 is encircled by a helical spring 41 which is disposed intermediate the boss 24 and the knife formed by the strips 27, 28, and 29.

Assuming, for example, that the parts are in the position depicted in Figs. 3, 4, and 8, it will be observed that if the operator presses upon the button 38, the locking catch 31 will be forced toward the left in Figs. 5, 7, and 8, the web 33 will thereby be carried or pushed out of the notch 30, and the helical spring 41 will quickly snap the stem 25 and the knife carried thereupon from the position indicated in Figs. 3, 4, and 8 to the position depicted in Figs. 2 and 5; hence, to push the button 38 toward the left in Figs. 5 and 7 will secure the release of the knife and will open a part of the ignition circuit. As will best appear from Figs. 2, 3, and 4, the conducting members 28 and 29 are insulated from each other and the current cannot pass directly from the conducting plate 12 to the conducting plate 19, but the current must pass through the generator or battery 7 as it travels from one of said plates to the other.

From the binding-post 16 a wire 42 leads to the binding-post 43, which is in suitable electrical connection with the plate 44 and spring-contact 45. Another spring-contact 46, which is in vertical alinement with the spring-contact 45, is in electrical connection with the binding-post 47 from which the wire 48 extends to one pole of the self-starter. Upon the opposite side of the device are the binding-post 49, plate 50, spring-contact 51, spring-contact 52, plate 53, and binding-post 54, which are substantial duplicates of the parts just described.

The vertically slidable yoke 55 bears the downwardly depending arms 56 and 57. The conducting strip 58 is secured to said arm 56, being insulated therefrom at 59, and said arm 58 carries the conducting fingers 60 and 61 which engage, respectively, with the spring-contacts 45 and 46 when the parts are in the position shown in Figs. 2 and 4, but not when the parts are as shown in Fig. 3. To the arm 57 is fastened a conducting member 62 insulated at 63 and bearing conducting fingers 64 and 65 adapted to engage the spring-contacts 51 and 52. When the parts are as shown in Figs. 2 and 4, therefore, electrical connection is established between the spring-contacts 45 and 46 on one side and 51 and 52 on the other, whereas, when the parts are as shown in Fig. 3, the circuits are broken.

The slidable yoke 55 carries a layer of insulation 66 which is adapted to prevent electrical connection between said slidable yoke 55 and the knife-switch formed of the insu-

lation 27 and conducting members 28 and 29. The yoke itself is bolted or riveted at 67 to the sliding plate 68 which passes through the slotted guide 69. The lower edge 70 of the plate 68 is beveled, and suitable cams (not shown in the drawings) are provided whereby revolution of the cylinder 71, which, of course, can be turned only by an appropriately-shaped key fitting into the keyhole 72, will move the sliding plate 68 from the position of Fig. 2 to the position of Fig. 3, or the reverse. The rotating cylinder 71, the tumblers which are actuated thereby, the fixed cylinder 73, and the shell 74 are old and well-known in the art and no particular novelty is claimed therefor, but the parts must be so arranged that the key can be withdrawn from the keyhole 72 only when the sliding yoke 55 is at the lowest point of travel (Figs. 2 and 4). The outer casing 40 is perforated at 75, said perforation being of just the right size and in the right position to fit over the fixed cylinder 73, and a plate 76 carrying the pin 77, which passes through a suitable perforation 78 in the casing 40, normally closes the perforation 75. Said pin 77 is carefully insulated at 79, but is in electrical connection with the pin 80. A pair of spring-contacts 81 and 82 insulated from each other and connected, respectively, to binding-posts 83 and 84 are adapted to be engaged by the pin 80 and electrical connection established between the same whenever the pivoted plate 76 is swung from the full line position (Fig. 1) toward or to the dotted line position. From the binding-posts 49 and 54, wires 86 and 85 extend to the self-starter, and the wire 87 is connected to the binding-post 22, it being understood, of course, that either through the framework of the machine, or otherwise, a circuit is completed between the wires 48 and 87.

The operation of the device is as follows: Assuming that the different parts are in the positions depicted in Fig. 2, the operator inserts the key in the keyhole 72 and rotates the revolving cylinder 71 in one direction. This forces the sliding yoke 55 upwardly in Fig. 2 and carries the same to the position of Fig. 3, and as the sliding yoke 55 thus moves it bears upon the knife formed of the members 27, 28, and 29 and forces same to the position of Fig. 3. When the parts are in the position of Fig. 3, the current can pass in an obvious manner from the binding-post 11 through the members 12, 13, 29, 14, 15, 16, 42, 43, and 44 as far as the spring-contact 45, but at that point there is a break in the circuit. If, thereupon, the operator will turn the key in the opposite direction, the sliding yoke 55 will be carried from the position of Fig. 3 to the position of Fig. 4, thus establishing electrical connection between the members 45 and 46 on one side

and 51 and 52 on the other, closing both of the circuits. When the parts are in the position of Fig. 4, the automobile can operate because all of the circuits are closed, but when the parts are in the positions indicated in either Fig. 2 or Fig. 3, the automobile cannot operate because one or both of the circuits will be broken. If the operator wishes to break the circuits and stop the operation of the automobile, he can do so instantaneously by pressing upon the button 38 and forcing same toward the left (Figs. 5 and 7) because, in that manner, the web 33 is carried out of the notch 30, thus permitting the helical spring 36 to uncoil and force the knife-switch downwardly until the contacts 13, 14, 17, and 18 engage the insulation 27, thus breaking the ignition circuit and rendering the automobile inoperative. To render the machine operative again, the operator must turn the rotating cylinder in one direction so as to force the sliding-yoke 55 upwardly and carrying all parts to the position of Fig. 3; then he must rotate the cylinder 71 in the opposite direction carrying the sliding-yoke 55 to the position of Fig. 4, but leaving the members 27, 28, and 29 in the upward position to which they have been moved. When the sliding-yoke 55 reaches the position of Fig. 4, electrical connection is established between the spring-contacts 45 and 46 on one side of the device and 51 and 52 upon the other, and thereby both of the circuits are closed. The operator can, thereupon, withdraw the key and the machine will be ready for operation.

From the binding-posts 83 and 84, wires (not shown) extend to the horn, and, in this manner, the horn will sound whenever the guard 76 is pushed to one side so as to permit the key to be inserted in the keyhole 72. This sounds a warning to the owner of the machine in case an unauthorized person shall endeavor to unlock the device. Sun-dry changes in the details of construction and operation of parts may be made without departing from the scope of the invention.

I claim as my invention:

50 1. In a device of the character described, the combination of a knife, a pair of stationary contacts, said knife being adapted to engage both of said contacts and establish electrical connection therebetween when said knife is in one position, a sliding yoke adapted to force said knife in one direction, a second pair of stationary contacts, a member carried by the yoke and adapted when said yoke is in one position to establish electrical connection between said second-mentioned contacts, and means coöperating with said yoke adapted to move said yoke from one position to another position.

60 2. In a device of the character described, the combination of a knife composed of an

insulating member and a conducting member, a pair of stationary contacts adapted to engage said insulating member when said knife is in one position and adapted to engage said conducting member when said knife is in another position, a sliding yoke adapted to force said knife to the position where the conducting member carried thereupon engages said contacts, a second pair of stationary contacts, a member carried by the yoke and adapted to establish electrical connection between said second-mentioned contacts when said yoke is in one position, and key-operated means adapted to move said sliding yoke.

65 3. In a device of the character described, the combination of a knife composed of an insulating member and a conducting member, a pair of stationary contacts adapted to engage said insulating member when said knife is in one position and adapted to engage said conducting member when said knife is in another position, a sliding yoke adapted to force said knife to the position where the conducting member carried thereupon engages said contacts, a second pair of stationary contacts, a member carried by the yoke and adapted to establish electrical connection between said second-mentioned contacts when said yoke is in one position, and key-operated means adapted to move said yoke.

70 4. In a device of the character described, the combination of a knife composed of an insulating member and a conducting member, a pair of stationary contacts adapted to engage said insulating member when said knife is in one position and adapted to engage said conducting member when said knife is in another position, a sliding yoke adapted to force said knife to the position where the conducting member carried thereupon engages said contacts, a second pair of stationary contacts, a member carried by the yoke and adapted to establish electrical connection between said second-mentioned contacts when said yoke is in one position, an insulating member intermediate said knife and said yoke, and key-operated means adapted to move said yoke.

75 5. In a device of the character described, the combination of a knife composed of an insulating member and a conducting member, a pair of stationary contacts adapted to engage said insulating member when said knife is in one position and adapted to engage said conducting member when said knife is in another position, a sliding yoke adapted to force said knife to the position where the conducting member carried thereupon engages said contacts, a second pair of stationary contacts, a member carried by the yoke and adapted to establish electrical connection between said second-mentioned contacts when said yoke is in one position, an insulating member intermediate said knife and said yoke, and key-operated means adapted to move said yoke, electrical connection being established between said second-mentioned contacts when said yoke is removed from said knife.

80 6. In a device of the character described, the combination of a knife composed of an insulating member and a conducting member, a pair of stationary contacts adapted to engage said insulating member when said knife is in one position and adapted to engage said conducting member when said knife is in another position, a sliding yoke adapted to force said knife to the position where the conducting member carried thereupon engages said contacts, a second pair of stationary contacts, a member carried by the yoke and adapted to establish electrical connection between said second-mentioned contacts when said yoke is removed from said knife.

- of stationary contacts, a member carried by the yoke and adapted to establish electrical connection between said second-mentioned contacts when said yoke is in one position, 8
 8 an insulating member intermediate said knife and said yoke, and key-operated means adapted to move said yoke, the connection between said second-mentioned contacts being broken when said knife is in the position where the conducting member carried thereupon engages the first-mentioned contacts and where the yoke is in engagement with or close proximity to said knife. 10
 6. In a device of the character described, 15 the combination of a knife, a pair of stationary contacts, said knife being adapted to engage both of said contacts and establish electrical connection therebetween when said knife is in one position, a slidable yoke adapted to force said knife in one direction, a second pair of stationary contacts, a member carried by the yoke and adapted when said yoke is in one position to establish electrical connection between said second-mentioned contacts, a stem upon which said knife is mounted, a catch adapted to co- 20
 20
 25
- operate with said stem and lock said stem in one position, and means to actuate said stem and said knife when said stem is disengaged from said catch. 30
 7. In a device of the character described, the combination of a knife, a pair of stationary contacts, said knife being adapted to engage both of said contacts and establish electrical connection therebetween when said knife is in one position, a slidable yoke adapted to force said knife in one direction, a second pair of stationary contacts, a member carried by the yoke and adapted when said yoke is in one position to establish electrical connection between said second-mentioned contacts, a mounting for said knife adapted to support the same, a spring-controlled locking means adapted to coöperate with said mounting and normally retain 45 said knife in one position, and means to cause said knife to move to another position when said mounting member is disengaged from said locking means. 40
 In testimony whereof I affix my signature. 50

FRIEDRICH L. HEYER.
